UNITED STATES PATENT OFFICE.

THEODORE C. HOLLNAGEL, OF MILWAUKEE, WISCONSIN, ASSIGNOR, BY MESNE ASSIGNMENTS, TO THE HUGHES-KEENAN COMPANY, OF MANSFIELD, OHIO, A CORPORATION OF OHIO.

TRUCK.

Application filed June 19, 1922, Serial No. 569,516. Renewed March 17, 1928.

This invention relates to certain new and useful improvements in trucks and refers more particularly to means for discharging a load from the body thereof.

- 5 The present manner of constructing trucks equipped with means for facilitating discharging of the load therefrom is by tiltably mounting the body and raising its inner end either by hoist cables or hydraulic means.
- 10 This manner of discharging the contents of the truck body is objectionable in that excessive power is required and furthermore that its operation is not as smooth or efficient as is desired.
- 15 Therefore, having the above in mind, it is one of the objects of this invention to provide an improved type of means for discharging material from a truck body in which the body is fixed and discharged by 20 being bodily shifted toward the discharge end.

It is another object of this invention to provide a load receiving body having a movable bottom and means for moving the bottom 25 to and from the body discharge end, whereby material may be readily discharged from the body.

Another object of this invention resides in the provision of a device of the character described having a movable bottom or floor for the load receiving body thereof equipped with means whereby a load within the body is bodily shifted toward the discharge end when the movable bottom is moved theretowards.

It is another object of this invention to provide a load receiving body having means for adjusting the capacity thereof.

This invention has for a further object to 40 provide a device of the character described having means for scraping the sides of the load receiving body to prevent adhering of material to the walls thereof after the load has been discharged therefrom.

45 A still further object of this invention resides in the provision of a device of the character described which may be applied to trucks now in use or to trucks at the time of their manufacture.

50 With the above and other objects in view which will appear as the description proceeds, my invention resides in the novel construction, combination and arrangements of

parts substantially as hereinafter described and more particularly defined by the appended claims, it being understood that such changes in the precise embodiment of the herein disclosed invention may be made as come within the scope of the claims.

In the accompanying drawings, I have 60 illustrated one complete example of the physical embodiment of my invention constructed according to the best mode I have so far devised for the practical application of the principles thereof, and in which:

65 Figure 1 is a side view of the rear portion of a truck equipped with my invention, parts thereof being broken away and in section;

70 Figure 2 is a sectional view taken transversely through Figure 1 on the plane of line 2—2;

75 Figure 3 is a fragmentary detail view illustrating the construction of the movable load receiving body floor;

Figure 4 is a detail view illustrating the manner of connecting the movable floor with a power takeoff shaft of the truck power unit;

80 Figure 5 is a side fragmentary view of the rear portion of a truck equipped with a slightly modified form of movable load receiving body bottom, and

85 Figure 6 is a fragmentary detail view illustrating the means carried by the movable load receiving body floor inner end for removing material from the body side walls.

Referring now more particularly to the accompanying drawings, in which like numerals designate like parts throughout the several views, the numeral 10 designates the chassis frame of an automotive truck which is supported at its rear by drive wheels 11 and at its forward end by steering wheels, not shown. Mounted on the chassis frame, 95 rearwardly of the power unit, not shown, is a load receiving body supporting frame comprising longitudinal side channel beams or sills 12 that are spaced from the chassis frame by transverse beams or bars 13 and 100 carry, at spaced intervals, transverse bars or channel beams 14 upon which is mounted a load receiving body 15 having side walls 16 and a swinging discharge end gate 17.

105 Gate 17 is pivotally mounted at its upper end, as at 18, and is adapted to be releasably

locked in closed position by a locking rod 18 controlled by an actuating lever 20. The bottom of the body is formed by a plurality of transverse plates 21, the intermediate portions of which are offset, as at 22, to dispose their ends on different planes whereby the ends of adjacent plates overlap and form a substantially level floor.

Each plate 21 has one or more links 23 secured thereto, and adjacent longitudinally aligned links are pivotally connected, as at 24, to form sprocket chains for connecting the plates. There are a sufficient number of plates 21 so that, with the parts in their position illustrated in Figure 1, the bottom will extend throughout the entire length of the body. The opposite ends of the sprocket chains formed by links 23 are connected by suitable cable or sprocket chain means 25 which train about sprocket wheels 26 and 27 mounted on shafts 28 and 29 journaled in bearings disposed adjacent the forward and rear ends of the truck body, respectively. The shafts 28 and 29 and sprocket wheels 26 and 27 are so positioned that plates 21 are on the proper plane to form the floor of the body.

Disposed along the lower longitudinal edge of each side 16 is a strip 30 on which the adjacent ends of plates 21 ride and the intermediate portions of said plates are braced by longitudinally extending strips 31 connecting the brace beams 14. The material within the truck body is prevented from working over the edges of the plates by guards 32 carried by sides 16 and inclined inwardly therefrom to overlie the ends of the movable floor, see Figures 1 and 2.

As before described, the rear discharge end of the truck body is closed by the swinging gate which may be opened to permit discharge of materials therefrom. The discharging of material from the truck body is accomplished by moving the plates, forming the bottom of the body, toward the discharge end and to insure the positive expelling of all material, an end plate member or partition 33 is carried by the inner end of the movable floor and insures the bodily shifting of the material with the movable floor.

Member 33 has its inner end rigidly secured to one of the innermost plates 21, as at 34, and is braced by a plate 35, the upper longitudinal edge of which is pivotally secured to plate member 33 at an intermediate point, as at 36, and the lower longitudinal edge of which is detachably secured, as at 37, to one of the plates 21 spaced inwardly from the plate carrying said end member. In this manner, member 33 is not only braced but means are provided whereby the positive discharge of all material is assured when the bottom is moved to position member 33 at its extreme outermost position, as best illustrated by the dotted lines in Figure 1.

Member 33 not only insures the bodily shifting of the load with the movable floor, but permits the ready adjustment of the body to measure any part of a load. As for instance, if it is desired to measure a half of a load, member 33 is shifted to a position medially of the body.

The movable floor is actuated by rotating shaft 29 in either direction, according to whether it is desired to return the floor to normal position or to discharge the contents of the truck body, and this is accomplished by connecting said shaft with a drive shaft 38 by sprocket wheels 39 and 40, and a sprocket chain 41. The shaft 38 is journaled in bearings carried by beams 12 and is connected, by gearing 42, with a drive shaft 43 journaled in bearings carried by beams 12.

Journalized in certain of the transverse beams 13, adjacent shaft 43, is a shaft 44, which is drivingly connected with the shaft 43, by gearing 45, and has fixed thereon a gear wheel 46 and a sprocket wheel 47, the sprocket wheel 47 being at all times in drive connection with a sprocket wheel 48 freely rotatably mounted on a counter shaft 49 disposed adjacent shaft 44. Gear 46 is adapted to be selectively meshed with a gear 50 slidably splined on shaft 49 and having a clutch face which is engageable with a corresponding clutch face carried by sprocket wheel 48, when said gear is disengaged from gear 46 and is at one limit of movement, whereby sprocket wheel 48 may be made fast to the counter shaft.

The counter shaft 49 has a drive sprocket 52 mounted thereon which is connected, by a sprocket chain 53, with a sprocket wheel 54 freely rotatably mounted on a shaft 55 which derives its power from the power unit of the truck, not shown. As best illustrated in Figure 4, sprocket wheel 54 is drivingly connected and disconnected with shaft 55 by a clutch member 56 which is capable of actuation by a lever 57 positioned adjacent the driver's seat. Gear 50 may be meshed with gear 46 or actuated to make sprocket 48 fast with the counter shaft by manipulation of a pedal 58 positioned adjacent the driver's seat.

When it is desired to discharge a load within the truck body, pedal 58 is actuated to mesh gears 50 and 46 and lever 57 is moved to make sprocket wheel 54 fast to shaft 55, as a result of which the movable floor is then actuated to advance member 33 toward the discharge end of the truck as will be readily obvious. After the load has been discharged and it is desired to place the truck body in condition to receive another load, the drive is reversed by disconnecting gears 50 and 46 and shifting gear 50 to make sprocket wheel 48 fast to the counter shaft.

Any material tending to adhere to the sides 16 of the truck body is removed by

means of scrapers 59 carried by member 33 and yieldably urged to engagement with the side walls by a spring 60', see Figure 6.

In Figure 5 I have illustrated a slightly modified form of my invention in which the outer end of the movable floor winds upon a drum 60 when the truck load is being discharged, drum 60 being driven with shaft 29 by a sprocket and chain connection 61, but at a slower speed to compensate for its increase in diameter as the floor is wound therearound.

In this form of my invention the drive is illustrated as by means of a hand crank 62 carried by a shaft 63 which is in geared connection with shaft 29, shaft 29 and shaft 64 of drum 60 being carried by combined braces and shields 65. Guards 66 are employed to prevent slipping of links 23 off the sprocket wheels 27.

To insure the easy control of the movable floor, a roller 67 is freely rotatably mounted on each pivot 24. The rollers 67 project below the links 23 and track on a floor or other support 68 to relieve the load from being directly carried by the chains formed by links 23.

What I claim as my invention is:

1. A device of the character described, comprising a load receiving body having a discharge end, an end member normally positioned adjacent the end of the body remote from the discharge end, means operable to move said member toward the discharge end of the body to expel material within the body therefrom through the discharge end, scrapers secured along the sides of said member, and spring means yieldably urging said scrapers to engagement with the walls of the load receiving body to remove material adhering thereto as said member is moved.

2. A device of the character described, comprising a load receiving body having a stationary floor, a movable floor for the body, longitudinal supporting strips mounted on the stationary floor in parallel, spaced relation and supporting and spacing the movable floor from the stationary floor and providing longitudinal braces for the movable floor, a plurality of sprocket chains longitudinally secured to the movable floor in spaced relation medially of said supporting strips, and roller members carried by the sprocket chains and projecting therebeneath to track on said stationary floor whereby the movable floor is supported and braced by said supporting strips and the sprocket chains.

3. An automotive truck, comprising a load receiving body having a discharge end, roller means mounted at the opposite ends of the body, a sectional movable floor for the body trained about said roller means whereby the roller means define the ends of the body floor, means operable to rotate

the roller means to move the sectional floor toward the discharge end of the body to discharge a load supported thereon, an end member mounted on the movable floor and extending across the side walls of the body, 70 said end member being positioned at a point adjacent the inner ends of the body side walls when the movable floor is in load receiving position, a plate brace extending across the width of the body, means securing the upper end of the plate brace to a medial portion of the movable end member, and means securing the lower end of the plate brace to the movable floor at a point spaced outwardly from the end member to 80 define, with that portion of the end member above the plate brace, an inner closed end for the body which is inclined outwardly toward the point of discharge, whereby movement of the floor to discharge position 85 disposes the lower end of said plate brace at the roller means adjacent the discharge end to insure the complete discharge of material from the body.

4. An automotive truck, comprising a 90 load receiving body having a discharge end, roller means mounted at the opposite ends of the body, a sectional, movable floor for the body trained about said roller means whereby the roller means define the ends 95 of the body floor, means operable to rotate the roller means to move the sectional floor toward the discharge end of the body to discharge a load supported thereon, an end member mounted on the movable floor and extending across the side walls of the body, 100 said end member being positioned at a point adjacent the inner ends of the body side walls when the movable floor is in load receiving position, a plate brace extending across the width of the body, means pivotally securing the upper end of the plate brace to a medial portion of the movable end member, and means detachably securing the lower end of the plate brace to the movable floor at a point spaced outwardly from the end member to, with that portion of the end member above the plate brace, define an inner closed end for the body which is inclined outwardly toward the point of discharge, whereby movement of the floor to discharge position disposes the lower end of said plate brace at the roller means adjacent the discharge end to insure the complete discharge of material from the body, said plate 110 brace being movable on its pivot to lie against the upper portion of the end member.

5. A device of the character described, 125 comprising a load receiving body having side walls and a stationary floor extending throughout the entire area of the body, a movable floor for the body, longitudinal supporting strips mounted on the stationary floor adjacent the side walls and supporting 130

- the ends of the movable floor which are spaced from the side walls, and guard members secured to the side walls and overlapping the adjacent ends of the movable floor.
- 5 6. In combination with a load carrying body, a movable bottom comprising a plurality of bent, sheet metal plates having overlapping portions so shaped and arranged as to present a substantially flat
- 10 upper surface and to prevent material from escaping between the plates; a plurality of longitudinal chains having links secured to the plates; a support below the chains; anti-friction rollers on the chains to move on the support; and means to move the bottom on the support.
- 15 7. In combination with a load carrying

body, a movable bottom comprising a plurality of overlapping sheet metal plates extending across the body with adjacent plates 20 in close contact so as to prevent material from entering between the overlapping portions of the plates; longitudinal sprocket chains each having links secured to the plates; rollers on some of the links; a support over which the rollers run; sprocket wheels adjacent to the opposite end of the body; and power driving means operatively connected to the sprocket wheels to move the bottom in either direction.

25 30 In testimony whereof I affix my signature.

THEODORE C. HOLLNAGEL.
